UNITED STATES PATENT OFFICE

GUSTAVE F. CORDUAN, OF CHICAGO, ILLINOIS, ASSIGNOR TO CORDUAN MANUFACTURING COMPANY, OF CHICAGO, ILLINOIS, A CORPORATION OF ILLINOIS

CHAIR

Application filed July 26, 1929. Serial No. 381,978.

This invention relates to certain new and useful improvements in chairs, and more particularly to an improved chair of the folding type adapted for use with card tables, or for similar purposes.

The general object of the invention is to provide a substantially all metal folding chair that is strong and rigid, of light weight in proportion to its strength, easy to collapse or erect for use, and economical to manufacture.

Another object is to provide a chair consisting of a few simple metal parts, many of which are interchangeable or reversible, and which parts are easily assembled.

Another object is to provide a metal chair that presents an attractive appearance, is adapted for surface ornamentation and is comfortable when in use.

Another object is to provide a chair which is strong and rigid when erected for use, but which may be easily folded into very compact form for storage.

Another object is to provide an improved form of cushioned supporting member for use in the seat or back of a chair.

Another object is to provide an improved form of reinforced metal leg for use in a chair of this type.

Another object is to provide an improved form of cushioned foot construction for the leg of a metal chair.

Another object is to provide an improved method of anchoring the hinged brackets within the metal leg members.

Another object is to provide an improved form of reinforced seat for a chair of this type.

Another object is to provide an improved form of holding seat and leg construction for a metal chair.

Other objects and advantages of this invention will be more apparent from the following detailed description of one approved construction of chair involving the principles of this invention.

In the accompanying drawings:

Fig. 1 is a side elevation of the chair, in position for use, the chair being shown folded in dotted lines.

Fig. 2 is a front elevation of the chair in folded position.

Fig. 3 is a central vertical section through the chair, taken substantially on the line 3—3 of Fig. 2, but with the chair shown unfolded ready for use.

Fig. 4 is a rear elevation of the chair.

Fig. 5 is a front elevation of the chair back, the back being partially broken away to show the interior construction.

Fig. 6 is a detail sectional view illustrating a fastening means used in the back and seat construction.

Fig. 7 is a bottom plan view of the seat, the view being taken substantially on the line 7—7 of Fig. 1, looking in the direction of the arrows.

Fig. 8 is a central vertical section through one of the rear legs.

Fig. 9 is an inside elevation of one of the cushioned feet.

Fig. 10 is a horizontal section through the leg construction, this view being taken substantially on the line 10—10 of Fig. 8.

Fig. 11 is a detail horizontal section, taken substantially on the line 11—11 of Fig. 1.

Fig. 12 is a detail vertical section through the rear hinge construction, taken substantially on the line 12—12 of Fig. 7.

Fig. 13 is a similar view through one of the front hinges, the view being taken substantially on the line 13—13 of Fig. 7.

Fig. 14 is a detail vertical section through the slide mechanism, the view being taken substantially on the line 14—14 of Fig. 7.

Fig. 15 is a perspective view of the slide member.

Fig. 16 is a perspective view of the latch member.

The chair consists essentially of a rigidly assembled back construction comprising a cushion back member A, a pair of rear legs B, and an intermediate bracing structure designated generally at C; a cushioned seat member D hingedly connected with the back structure; a pair of front legs E hingedly connected with the seat D; a spacing structure indicated generally at F for maintaining the several legs in properly spaced relation; and a bracing strut construction in-

55

60

dicated generally at G for holding the parts in rigid relationship when unfolded for use.

The back A comprises a sheet metal plate or stamping 1 having upwardly and inwardly edge portions 2 so as to form a dish for receiving the cushion. The member 1 is grooved or corrugated as indicated at 3 so as to both reinforce the back and present an ornamental appearance on its rear side. 10 This ornamentation 3 comprises substantial- ly vertical channel portions 4 which serve to receive the upper end portions of the rear legs B and brace the same. The cushion comprises an inner filler 5 in the form of a 15 rather thick plate or slab of suitable fibrous material which is preferably light but some- what elastic. A pad 6 of suitable soft wad- 20 ing material is placed over the filler 5. A flexible sheet covering 7 of fabric, imitation leather, or similar material is placed over the pad 6. The covering 7 may be suitably 25 ornamented on its exposed side. The cushion is preferably assembled as a unit by glu- 30 ing the inturned edges of covering 7 onto the back of filler block 5. The cushion is 35 positioned within the dished back plate 1 and is then held in place by a metal binding strip 8 of semi-circular cross section, this chan- neled binding strip being placed over the 40 edge portion of the cushion and the inward- 45 ly rounded edge portion 2 of the back plate. For fastening the ends of the binding channel member 8 in position, a metallic staple 9 is passed through mating openings in the 50 upturned edge portion 2 of plate 1 and the end portion of the binding strip 8, and the 55 ends of the staple bent down as indicated in Fig. 6. In order to prevent the staple from 60 being pushed inwardly against the cushion during this clamping process, the staple is 65 welded to the edge portion 2 as indicated at 10.

Each rear leg B comprises an inner metal rod or stiffener 11 around which is bent a 45 sheet metal covering member 12, the edges of this metal member meeting along a line 13 on the inner side of the leg. The rear exposed face of the covering 12 can be cor- 50 rugated or stamped to give it any desired ornamental configuration as indicated at 14. A similarly ornamented metal covering strip 55 15 may be secured over the joint 13 on the front face of the leg on the exposed portions between the back A and seat D and at other 60 places if so desired. The stiffener rod 11 may terminate short of the upper end portion 16 of the legs B, which are flattened and inserted through openings 17 in the back plate 1 and extended up into the channels 4 behind the 65 cushion where they are anchored in place by means of rivets 18.

The improved foot construction com- 65 prises a metal shoe 19 secured about the lower end of the leg B. This shoe comprises a semi-spherical lower cap portion 20 of great-

er diameter than the lower end of the leg so as to form an outwardly extending rib 21 from which an ornamental plate portion 22 extends up along the rear faces of the leg, and a pair of side arms or clips or tabs 23 are bent around the lower portion of the leg so as to meet substantially along the di- 70 viding line 13. A rubber pad 24 is placed over the lower rounded shoe portion 20 and secured in place by an annular cap 25 having a lower inwardly extending flange 26 en- gaged over pad 24, the upper edges of the cap 25 being crimped inwardly at 27 over the outwardly extending flange 21 of shoe 19. 75

A hinge plate 28 is secured in each leg B at the proper height to support the seat D. The plate 28 comprises a portion 29 bent around the rod 11, from one side of which extends the hinge lug or bracket 30. A sec- 80 ond lug 31 extends inwardly parallel with hinge lug 30 and is then bent at right angles to form an attaching plate 32 from which extends downwardly and outwardly an aux- 85 iliary attaching plate 33. The hinge plate 28 is held at the proper elevation in the leg B and prevented from movement longitudinally of the leg by crimping or bending the edge covering plate 12 inwardly above and below this plate to the line 13, as already 90 described. The covering member 12 is sepa- 95 rated at the height of the hinge plates suffi- ciently to permit the bracket arms or lugs to project at the inner face of the leg. Similar hinge members 34 are secured in the legs B at points adjacent the lower ends of these 100 legs, each hinge plate 34 comprising an in- 105 wardly projecting hinge lug or bracket 35 and a laterally projecting attaching plate 36 from which projects upwardly and in- 110 wardly an auxiliary attaching plate 37. Sheet metal spacing bars or struts 38 are spot-welded at their ends to the respective 115 pairs of attaching plates 32 and 36. Similar diagonally extending bracing plates or struts 39 are spot-welded at their outer ends to the several attaching plates 33 and 37 and at their inner ends to a central plate 40, which may be of a circular or other ornamental configuration. The struts 38 and 39 are preferably given a corrugated or other 120 ornamental configuration corresponding to the covering members 12 and 15 of the legs, and the ornamental stamping 3 and 4 in the back plate 1. The lower hinge plates 34 are held in place within the legs by crimping the covering sheet 12 inwardly above and below the bracket members, as already de- 125 scribed in connection with the upper hinge plates.

The front legs E may be made of the same general construction as the rear legs B, and are provided with similar foot members at their lower ends. However, sufficient strength can be obtained without the inner stiffening rods 11, and these rods have been 130

omitted in the example here shown. Lower hinge plates are centrally looped at 41 to fit within the sheet metal leg member and are formed with integral rearwardly projecting hinge lugs 42 and laterally projecting attaching plates 43. The looped portion 41 is inserted within the leg E and has portions 41' extending upwardly and downwardly within the leg beyond the plates 42 and 43. The flanges of the sheet metal leg are crimped inwardly above and below the plates 42 and 43 to hold the hinge member from movement lengthwise of the leg. A bracing strut or bar 44 formed of sheet metal bent into flattened tubular form connects the attaching plates 43 and is spot-welded thereto. The exposed face of bracing member 44 is corrugated or ornamented in the same manner as the legs already described.

The side links F have the same general form as the bracing rod 44 just described, with their end portions 45 flattened and perforated to receive attaching pins or rivets 46 by means of which the links are pivoted at their front and rear ends to the hinge lugs 42 and 35 respectively. A sheet metal hinge plate 47 is bent to fit within the upper end portion of leg E and is formed with a rearwardly projecting hinge lug 48. The hinge member 47 is welded or riveted within the upper portion of the leg E.

The seat D has the same general construction as the back member A first described. It comprises a base plate 49 of sheet metal which is ribbed or corrugated as indicated at 50 to give it additional strength and stiffness. The edges of plate 49 are upwardly and inwardly curved at 51 and the cushion member 52 is secured in place by an outer channeled binding strip 53, in the same manner as in the back member. The cushion 52 is exactly the same as the cushion of the back member except that it has a greater area and different outer contour.

Front hinge brackets 54 have hinge lugs 55 projecting downwardly through slots 56 in the base plate 49, and have horizontal arms 57 which are welded to the upper face of plate 49. The hinge lugs 55 are pivotally connected by hinge pins 58 to the hinge lugs 48 of the front legs E. The hinge members and legs are so proportioned that when the parts are swung to supporting position as shown in Figs. 1 and 13 the upper end of each leg E will rest directly against the lower face of plate 49 of seat D so that the weight supported by the chair is transferred directly from the seat to the legs and is not carried by the hinge bolts 58.

The rear hinge brackets 59 are secured to the seat in the same manner as the front hinge bracket 54, each bracket having a horizontally extending inner arm 60 welded to the upper face of base plate 49. The lower bracket arm 61 extends rearwardly in a vertical plane and is provided with a stiffening rib 62 and terminates at its rear end in a perforated ear 63 which receives the hinge rivet 64 by means of which the bracket is hinged to hinge lug 30 of one of the rear legs B. The hinge arm 61 is provided with a laterally projecting supporting lug 65 which engages and rests upon a lug 66 formed on the hinge bracket 30 when the seat is swung down to the position shown in Fig 3 so as to relieve the hinge pin 64 of the weight sustained by the seat D.

The base plate 49 of seat D is slit centrally from a point adjacent the front edge thereof to a point adjacent the rear edge, and the metal adjacent each side of this slit is depressed so that an open slot 67 is formed. A reinforcing cover plate 68 is positioned above the slot 67 and the depressed portions of the base plate and spot-welded at 69 to the upper surface of this plate 49 so as to form a guide channel 70 extending centrally from front to rear of the lower face of the seat. A guide member 71 (see Figs. 14 and 15) is conveniently formed by welding together two right-angled sheet metal members so as to form a pair of oppositely projecting horizontal side arms 72 adapted to slide in the channel 70 and a downwardly projecting portion 73 adapted to extend down through the open slot 67 and slide therein. The vertical member 73 is formed with a perforated hinge lug 74 and a latch lug 75. The struts G, which may be formed of flattened tubular sheet metal members similar to the members F already described, are pivotally connected at their upper ends by means of hinge rivet 76 to the hinge lug 74 on the slide 71. These struts G extend downwardly and outwardly as best shown in Figs. 2 and 14 and are pivotally connected at their lower ends to the lower hinge lugs 35 on the rear legs, by means of hinge bolts 46 as already described.

The latch member 77 (shown in perspective in Fig. 16) comprises a piece of sheet metal stamped to form a bottom central plate portion 78 having a locking recess 79 to receive the latch lug 75 on slide member 71, and a pair of upwardly extending side arms 80 perforated at 81 to receive a pivot pin. An operating arm 82 projects rearwardly from the central plate 78. A U-shaped sheet metal bracket member 83 is inserted from above through suitably spaced slots in the base plate 49, with its central portion held in place at one end of channel 70 and its perforated side arms 84 projecting downwardly and serving as hinge lugs to which the latch member 77 is pivoted by means of hinge pin 85. A coiled spring 86 engaged about the hinge pin 85 serves to normally hold the latch member in the locking position shown in Fig. 3, but by pressing up on the arm 82 the opposite arm of the latch member may be depressed to release the latch lug 75 of slide 71 from the opening 79 in latch member 77. The forward side of latch lug 130

75 is beveled as indicated at 75' so that the slide member will automatically engage with the latch when the slide is moved to operative position at the forward end of the guide channel.

It should now be apparent that with the chair in the operative position shown in Fig. 3, by merely grasping the front edge portion of seat D and the arm 82 of latch 77 with the thumb and fingers the latch is released and without changing this grasp the seat may be swung up to the folded position shown in Fig. 2 and in dotted lines in Fig. 1. During this upward swinging movement of the seat, the slide 71 will automatically move to the rear end of channel 70, and the front legs E and the bracing struts F and G will all swing up into substantial parallelism with the rear legs B. It will be noted that the lower front bracing bar 44 is bowed outwardly so that when swung up to the folded position shown in Fig. 2 it will curve outwardly around the struts G and thus permit a more compact assembly of the parts when in this folded position. When the chair is to be again erected for use, the operator merely grasps the seat D and swings it downwardly. The latch 77 automatically engages with the latch lug 75 when the seat D reaches a horizontal position and the parts of the chair are all held rigidly in this operating position. It will be noted that the weight-supporting parts of the chair are all of rigid and substantial construction and the legs are securely braced one from another. When the chair is in normal position, the seat rests directly upon the front legs and upon bracket members rigidly anchored in the rear legs so that the weight is not sustained by the pivot members. The seat and back cushions are readily detachable so that they may be repaired or replaced. Most of the metal chair parts are sheet metal stampings whereby any desired surface ornamentation may be easily applied. All exposed metal parts will be painted or enameled to properly harmonize with the covering of the cushion members. The majority of the metal parts are made of sheet metal stampings and the parts are quickly assembled by bending and stamping processes. Most of the parts are connected by spot welding, and pins or rivets are only needed for the hinge connections between the several relatively pivoted members.

55 I claim:

1. In a chair, a leg construction comprising an inner metal rod and a sheet metal covering bent about the rod so that the edges of the covering substantially meet along the inner vertical face of the leg, the outer surface of the covering being stamped into a decorative conformation, and an auxiliary covering strip secured over the inner face of the leg to cover the meeting edges of the first

strip, the auxiliary strip being stamped to conform with the outer face of the main covering.

2. In a chair, a leg construction comprising an inner metal rod and a sheet metal covering bent about the rod so that the edges of the covering meet along the inner vertical face of the leg, and a bracket member bent about the inner rod and having arms projecting outwardly, the edges of the covering being bent into abutting relation above and below the projecting arms to hold the bracket from movement longitudinally of the leg.

3. In a chair, a leg construction comprising a sheet metal member covering bent into tubular form so that the edges meet along the inner vertical face of the leg, and a bracket member looped to fit within the leg and having an arm projecting outwardly at substantial right angles to the leg, the edges of the covering being bent into abutting relation above and below the arm to hold the bracket from movement longitudinally of the leg.

4. In a chair, a leg comprising an inner metal rod and a sheet metal covering bent around the rod so that its edges meet along one vertical side of the leg, a metallic foot member comprising a plate adapted to engage the lower outer vertical face of the leg covering, a pair of tabs bent laterally about the inner face of the leg, and a bottom member downwardly convexed and covering the lower end of the leg members, a foot pad positioned beneath the bottom member, and an annular cap member enclosing the edges of the pad and crimped inwardly about the bottom member to hold the pad in position thereon.

5. In a chair, a leg comprising an inner metal rod and a sheet metal covering bent around the rod so that its edges meet along one vertical side of the leg, a metallic foot member comprising a plate adapted to engage the lower outer vertical face of the leg covering, a pair of tabs bent laterally about the inner face of the leg, and a bottom member downwardly convexed and covering the lower end of the leg members, a rubber pad positioned beneath the foot member, and an annular cap comprising a flange extending inwardly over the lower edges of the rubber pad, and an upwardly projecting annular wall that is crimped inwardly about the bottom foot member.

6. In a chair, in combination with a metallic back member, a pair of similar leg members each secured to the back at its upper end, each leg comprising an inner metal rod and a sheet metal covering bent about the rod so that the edges of the covering meet along the inner vertical face of the leg, a plurality of bracket members each having a portion bent around the rod of a leg and having a laterally projecting arm, the edges of the cover-

ing being bent into abutting relation above and below the arm to anchor the bracket in place against movement longitudinally of the leg, and metallic bracing struts connecting certain of the bracket arms and welded thereto.

7. In a chair, in combination with a metallic back member, a seat, and supporting members for the seat, a pair of similar leg members each secured to the back at its upper end, each leg comprising an inner metal rod and a sheet metal covering bent about the rod so that the edges of the covering meet along the inner vertical face of the leg, a plurality of sheet metal bracket members each bent about the rod of a leg and having its ends projecting laterally to form an arm and a hinge lug respectively, the edges of the covering being bent into abutting relation above and below the arm and lug to anchor the bracket in position against movement longitudinally of the leg, metallic bracing struts connecting certain of the bracket arms and welded thereto, and means for pivotally connecting the seat and supporting member to the several hinge lugs.

8. In a chair, in combination with front and rear legs, each leg being provided with upper and lower hinge lugs, and struts pivotally connecting the lower hinge lugs of the front and rear legs, a seat comprising a sheet metal base member, hinge lugs secured thereto and pivotally connected to the upper hinge lugs of the several legs, the base member being slit centrally from a point adjacent but spaced from its rear edge to a point adjacent the slit being pressed downwardly so as to form a depressed open slot, a cover plate welded to the base plate above the slot so as to complete a guide channel and reinforce the base-plate, a slide mounted in the channel and having a hinge lug projecting downwardly through the slot, and struts pivoted to the hinge lug and projecting downwardly and outwardly with their lower ends pivoted to the lower hinge lugs of the rear legs.

9. In a chair, in combination with front and rear legs, each leg being provided with upper and lower hinge lugs, and struts pivotally connecting the lower hinge lugs of the front and rear legs, a seat comprising a sheet metal base member, hinge lugs secured thereto and pivotally connected to the upper hinge lugs of the several legs, the base member being slit centrally from a point adjacent but spaced from its rear edge to a point adjacent the slit being pressed downwardly so as to form a depressed open slot, a cover plate welded to the base plate above the slot so as to complete a guide channel and reinforce the base-plate, a slide mounted in the channel and having a hinge lug and a lock-

ing lug projecting downwardly through the slot, a latch member pivotally mounted on the lower face of the base plate and adapted to engage the locking lug when the slide is at the front end of the channel, and struts pivoted to the hinge lug of the slide and projecting downwardly and outwardly with their lower ends pivoted to the lower hinge lugs of the rear legs.

10. In a chair, in combination with front and rear legs, each leg being provided with upper and lower hinge lugs, and struts pivotally connecting the lower hinge lugs of the front and rear legs, a seat comprising a sheet metal base member, hinge lugs secured thereto and pivotally connected to the upper hinge lugs of the several legs, the base member being slit centrally from a point adjacent but spaced from its rear edge to a point adjacent the slit being pressed downwardly so as to form a guide channel and reinforce the base-plate, a slide mounted in the channel and having a downwardly projecting hinge lug, and struts pivoted to this hinge lug and projecting downwardly and outwardly with their lower ends pivoted to the lower hinge lugs of the rear legs.

11. In a chair, in combination with front and rear legs, each leg being provided with upper and lower hinge lugs, and struts pivotally connecting the lower hinge lugs of the front and rear legs, a seat comprising a sheet metal base member, hinge lugs secured thereto and pivotally connected to the upper hinge lugs of the several legs, the base member being slit centrally from a point adjacent but spaced from its rear edge to a point adjacent the slit being pressed downwardly so as to form a guide channel and reinforce the base-plate, a slide mounted in the channel and having a downwardly projecting hinge lug and a locking lug, a latch member mounted on the lower face of the seat and adapted to engage the locking lug when the slide is at the front end of the guide channel, and struts pivoted to the hinge lug of the slide and projecting downwardly and outwardly with their lower ends pivoted to the lower hinge lugs of the rear legs.

12. In a chair, in combination with a leg, a metallic foot member comprising a plate engaging the lower outer vertical face of the leg, a pair of tabs bent laterally about the inner face of the leg, and a bottom member downwardly convexed and covering the lower end of the leg, a foot pad positioned beneath the bottom member, and an annular cap member enclosing the edges of the pad and crimped inwardly about the bottom member to hold the pad in position thereon.

13. In a chair, in combination with a leg, a metallic foot member comprising a plate engaging the lower outer vertical face of the

leg, a pair of tabs bent laterally about the inner face of the leg, and a bottom member downwardly convexed and covering the lower end of the leg and formed with outwardly projecting edge portions, a rubber pad positioned beneath the foot member, and an annular cap having inwardly extending edge flanges engaged about the projecting edge portions of the foot member and pad.

10

GUSTAVE F. CORDUAN.**15****20****25****30****35****40****45****50****55****60****65**
